UNITED STATES PATENT OFFICE.

LAWRENCE F. RYAN, OF NEW YORK, N. Y.

DESIGN FOR A TOY CAT USED IN PLAYING THE GAME OF TIP-CAT.

No. 39,604.

Specification for Design.

Patented Oct. 6, 1908.

Application filed May 6, 1908. Serial No. 431,287. Term of patent 7 years.

To all whom it may concern:

Be it known that I, LAWRENCE F. RYAN, a citizen of the United States, residing at New York city, borough of Manhattan, county of New York, and State of New York, have invented a new, original, and ornamental Design for Toy Cats Used in Playing the Game of Tip-Cat, of which the following is a specification, reference being had to the accompanying drawing, forming a part thereof.

The figure is a perspective view of a toy cat, showing my new design.

The design consists of a figure whose body, at its upper portion displays a plain flat face at angles to each other, the lower portion of said body being formed with downwardly and inwardly tapering faces leading from and corresponding to the said flat faces, and the top of the body is crowned by a knob head.

I claim—

The ornamental design for a toy cat used in playing the game of tip-cat, as shown and described.

LAWRENCE F. RYAN.
